SAFETY DEVICE FOR ELECTRICAL APPLIANCES

Patrick McIlveney, Devonport, Auckland,
New Zealand

Application July 19, 1934, Serial No. 736,083

4 Claims. (Cl. 200—142)

The invention relates to safety devices used with electrical appliances, to which current is supplied for heating purposes, and has for its object the provision of an improved form of safety device of that class, wherein parts of the safety device are held together by a fusible solder, so that upon the device becoming overheated, the solder fuses and permits the parts to separate, and be responsible for the cutting "off" of electric current to the appliance.

According to the invention there is provided in the electric circuit of the appliance a spring contact which is maintained closed by means of a detachable plate comprising portions united by a fusible solder, one of said portions being secured to the casing containing the switch, and the other of said portions acting on a spring contact supporting member to normally retain the spring switch in its closed position.

In order however, that the invention may be better understood it will be more particularly described with the aid of the accompanying drawing, where, as an example, the improved safety device is illustrated, as applied to a plug used with a domestic electric iron.

In the drawing:—

Figure 1 is a plan view of the plug,

Figure 2 an inside view of the portion thereof, containing the safety device,

Figure 3 a longitudinal sectional view thereof, and

Figure 4, a sectional elevation enlarged of the safety device itself.

As applied to a plug, 1 with a flexible lead 2 and guard 3 attached and adapted for use with an electric iron, or other appliance, the wires 4 of said lead 2 are connected to separate terminals 5, one of which is permanently electrically connected with one of the usual spring jaw contacts 6, by a bar 7, the other of said terminals 5 being electrically connected to a spring contact 8 which normally moves away from a stationary contact 9 electrically connected with the other spring jaw contact 6.

In order to keep the spring contact 8 against the contact 9, so that a closed circuit through the appliance to which the plug 1 is fitted, can be obtained, in the usual manner upon closing an external switch, a headed pin 10 of material which is a non-conductor of electricity is made to extend through a hole in the side of the plug 1 in which the contacts 8 and 9 are fitted, and a plate 11 is secured by a screw 16 to the plug 1, so as to push the pin 10 inwards against the contact 8 and the latter against the contact 9.

The plate 11 contains a hole 12 with a slight rim 11a encircling same and around which is secured to said plate by fusible solder 13, a flanged cup 14 (shown inverted in the drawing), containing a hole 15.

The plug 1 is recessed to accommodate the cup 14, the hole 15 in which receives the body of the screw 16, so that the latter holds the plate 11 in position with the pin 10 pushed inwards against the action of the spring 8, to maintain an electrical connection between the latter and the contact 9.

Upon the plug 1 becoming heated beyond a predetermined degree, the solder 13 melts, whereupon the plate 11 fails to withstand the opening action of the spring 8 transmitted through the pin 10, and permits itself to be pushed away from the cup 14, so that the spring 8 moves from the contact 9 and opens the electric circuit through the appliance.

To put the plug into normal working order again, a new plate 11 with a cup 15 attached by a solder as described, is procured and secured against and in the plug 1 as shown by the screw 16 to cause the pin 10 to reclose the contacts 8 and 9.

By providing the pin 10 with a head, it is prevented from falling out of the plug 1, following removal of the plate 11.

Ribs or guards 18 on the side of the plug 1 to which the plate 11 is fitted ensure that the latter can be secured to the plug, only one way to push inwards the pin 10 and also to ensure that said plate 11 will clear the housing on the appliance, in which the plug 1 is inserted in use, to enable the plate to function upon the solder melting.

Insulating partitions 19, separate the jaw contacts 6 from the contacts 8 and 9.

The casing 1 is in the usual two portions adapted to be secured together by the usual screw bolts 17 and the screw 16.

What I do claim and desire to obtain by Letters Patent of the United States of America is:—

1. A safety device for use with electrical appliances, comprising a casing, a spring contact, a recessed portion seated in and detachably secured to said casing, a flat plate portion, fusible solder securing said flat plate portion to the recessed portion, and fitting flat against the exterior of said casing; and a pin extending through said casing and being retained in position by said flat plate portion to press against and to retain the spring contact in its closed position.

2. A safety device according to claim 1, wherein the recessed portion is cup-shaped having a hole in the cup part thereof, and means extending

through said hole and means securing the recessed portion to the casing.

3. A safety device according to claim 1, wherein the recessed plate portion is cup-shaped and has 5 a hole therein, and wherein the flat plate portion contains a hole adapted to register with the cup-shaped portion when the recessed portion and the plate portion are soldered together, and securing means extending through the said casing, for 10 fastening the recessed portion and the plate portion to the casing.

4. A safety device according to claim 1, wherein the recessed portion, which is adapted to be secured to the casing, is formed separate from the plate portion, and contains a cup with a hole therein, and surrounded by a flange, said other 5 portion containing a hole surrounded by a rim around which latter said flange is adapted to be secured by the fusible solder.
